(57) **CLAIM**

The ornamental design for a guide arm and base plate of a hose reel, as shown and described.

DESCRIPTION

FIG. 1 is an elevated perspective view of the front of the guide arm and base plate of a hose reel;

FIG. 2 an elevated perspective view of the top of the guide arm and base plate of the hose reel;

FIG. 3 is a plan view of the left side of the guide arm and base plate of the hose reel;

FIG. 4 is a front elevation view of the guide arm and base plate of a hose reel;

FIG. 5 is an elevation view of the back of the guide arm and base plate of the hose reel;

FIG. 6 is the plan view of the right side of the guide arm and base plate of the hose reel;

FIG. 7 is the top elevation view of the guide arm and base plate of the hose reel; and,

FIG. 8 is the bottom elevation view of the guide arm and base plate of the hose reel.

The broken lines show environmental subject matter and form no part of the claimed design.
